Michael J. La Forte, Park Ridge, Ill., assignor to Vaughan Mfg. Co., Chicago, Ill., a corporation of Illinois

Application April 13, 1951, Serial No. 14,819

Term of patent 14 years

(Cl. D22—2)

To all whom it may concern:

Be it known that I, Michael J. La Forte, a citizen of the United States, residing at Park Ridge, in the county of Cook and State of Illinois, have invented a new, original, and ornamental Design for a Can Opener, of which the following is a specification, reference being had to the accompanying drawings, forming part thereof.

Fig. 1 is a front elevational view of a can opener, showing my new design;

Fig. 2 is a rear elevational view;

Fig. 3 is an end view looking at the can opener from the left side of Fig. 1;

Fig. 4 is an end view looking at the can opener from the right side of Fig. 1; and

Fig. 5 is a top plan view.

I claim:

The ornamental design for a can opener, substantially as shown.

MICHAEL J. LA FORTE.
